UNITED STATES PATENT OFFICE

170,715

BOWL

Wilma Doris Pusecker, Columbus, Ohio

Application October 18, 1951, Serial No. 17,009

Term of patent 3½ years

(Cl. D44—10)

To all whom it may concern:

Be it known that I, Wilma Doris Pusecker, a citizen of the United States, residing at Columbus, State of Ohio, have invented a new, original, and ornamental Design for a Bowl, of which the following is a specification, reference being had to the accompanying drawings, forming a part hereof.

Fig. 1 is a top plan view of a bowl, showing my new design;

Fig. 2 is a side elevational view thereof; and
Fig. 3 is a bottom plan view thereof.

The dominant features of my new design are shown in solid lines in the drawing.

I claim:

The ornamental design for a bowl, substantially as shown and described.

WILMA DORIS PUSECKER.
